Attorney

UNITED STATES PATENT OFFICE

CLARENCE H. HAGAN, OF ENID, OKLAHOMA

PLACARD HOLDER

Application filed February 8, 1930. Serial No. 426,945.

The present invention relates to placard holders and more particularly to placard holders adapted for use on railway cars or the like.

5 An object of this invention is to provide a holder of this character which is adapted to securely hold the desired placard on the side of the car where it will be readily visible.

Another object of this invention is to provide 10 a holder of this character which may be mounted on a railway car in the desired position along the side thereof where it will attract attention and which will securely hold the desired placard therein for an indefinite 15 period of time.

A further object of this invention is to provide 20 a holder of this character with suitable drainage or cleaning means so that the holder will not become clogged with cinders or rendered unfit for use due to inclement weather or the like.

The above and various other objects and 25 advantages of this invention will in part be described in and in part be understood from the following detailed description of the present preferred embodiment, the same being illustrated in the accompanying drawing wherein:—

Figure 1 is a detailed front elevation of a 30 device constructed according to the preferred embodiment of this invention;

Figure 2 is a similar view showing the method of inserting the placard;

Figure 3 is a similar view showing the device with the placard mounted therein; and

Figure 4 is a transverse section taken substantially on the line 4—4 of Figure 1.

Referring to the drawing wherein like numerals of reference designate corresponding parts throughout the several views, the numeral 10 designates the running board or side of a railway car. The railway car 10 in the preferred embodiment of this invention is a tank car or the like which is provided with a suitable running board or the like along the side thereof and on which a placard holder generally designated as 11 is adapted to be mounted.

A bracket 12 of substantially L shape is 50 adapted to have one leg thereof secured to

the running board 10 of the railway car and the other leg is adapted to be mounted in substantially vertical or upright position. A card holder 13 is adapted to be secured to the upstanding leg of the bracket member 55 12 by means of bolts or rivets 14 or the like. The card holder 13 may be constructed in any desired shape or configuration but in the preferred embodiment of this invention is constructed of a flat sheet of metal, the outer end 60 portions of which have been bent or reverted so as to form inwardly extending flanges 15.

The inwardly extending flanges 15 are adapted to be positioned in slightly spaced relation to the outer face portion of the sheet member 13 so as to permit a card or other indicia bearing member to be inserted therebetween.

The card holder 13 is provided along one edge portion thereof with a substantially enlarged flange member 16 and along the opposite edge portion with a substantially small inwardly extending flange member 17. The opposite end portions of the inwardly extending flange 17 preferably terminate in spaced 75 relation to the opposite edge portions of the base member 13 and are preferably angularly inclined so as to permit the ready insertion of a card within the holder.

The base member 13 is preferably mounted 80 upon the bracket 12 in such position that the bracket member extends diagonally across the plate 13 so that two abutting edge portions of the plate will be mounted in angular relation to the running board 10.

The flange members 15 and 17 have their adjacent edge portions positioned in spaced relation to each other as at 18 so that any cinders, water or the like will drain downwardly and outwardly of the holder 13. The base 90 plate 13 is provided with an aperture 19 spaced inwardly from the flange member 17.

A placard or indicia bearing member 20 is adapted to loosely engage the holder 11 between the base 13 and the inwardly extending flanges 15 and 16, the indicia bearing member 20 being pushed upwardly and sprung into position so that the lower edge portion thereof will pass the short flange 17 and thereby permit the card 20 to slide or 100

drop downwardly so as to be securely held on the holder by each of the inwardly extending flange members. The lower edge portion of the card member 20 is preferably 5 arcuately inclined as at 21 so as to facilitate inserting the member in the holder.

While the placard holder 11 has been particularly designed for use in connection with tank cars or the like, it will be obvious that its use is not limited to tank cars but that it may be used with equal facility on other vehicles or railway cars and where a car is provided with upstanding side portions, the bracket member 12 may be omitted and the 10 holder bolted or otherwise secured directly to the side of the conveyance.

In the use of this device, the bracket member 12 may be secured at any convenient position along the side portions of the car, and 15 the holder 11 bolted or otherwise secured to the bracket so that it will be mounted in substantially upstanding position. The placard 20 may be inserted in the holder 11, the placard bearing suitable indicia so as to properly 20 designate either the contents of the car or the routing thereof or any other desired indicia or legends.

Where it is desired to remove the card from the holder the card may be moved upwardly therein and by inserting a finger or the like in the opening 19 of the base member 13, the lower edge portion of the card may be forced outwardly so as to readily remove the card from the holder. The elongated flange member 16 is preferably of such length that it will permit the card to be pushed upwardly so that the lower edge portion of the card will clear the upper edge of the flange 17, and when the card is placed in the holder the 25 flange 16 will engage about one edge portion of the card after the same has been pushed downwardly so as to be engaged between the flange 17 and the lower edge portion of the base member 13.

The placard holder 11 together with the bracket member 12 are preferably constructed of substantially rigid metal, and the placard 20 may be constructed of cardboard, flexible or yieldable metal or the like.

It will, of course be understood that various changes and modifications may be made in the details of construction and design of the above specifically described embodiment of the invention without departing from the spirit thereof, such changes and modifications being restricted only by the scope of the following claims:

What is claimed is:—

1. In combination, a placard and a placard holder, said holder comprising a base, a plurality of flanges on said base and overlapping one face portion thereof, said flanges being arranged in pairs, each member of each pair being substantially parallel to the other member, one flange of one pair having the

ends thereof positioned in spaced relation to the adjoining ends of the flanges of the other pair, the flange opposing said one flange being substantially wider than said one flange, said placard being shorter in width than the distance between the outer marginal edge portions of said one flange and said wider flange whereby to permit movement of said placard beneath the flanges for removal or insertion thereof. 70

2. In combination, a holder, a placard adapted to be removably mounted in said holder, and a bracket member positioned on said holder in diagonal relation thereto whereby to mount said holder in diagonal so position, said holder comprising a base plate and a plurality of parallel flanges on said plate and extending inwardly of the marginal edge portions thereof, said flanges being arranged in pairs, one flange of one pair having the opposite ends thereof positioned in spaced relation to the adjacent ends of each of the flanges of the other pair, the flange opposing the one flange being relatively wider than said one flange, said placard being of a width narrower than the distance between the outer marginal edge portions of said one flange and said wide flange whereby to permit relative movement of the placard within the holder, said base plate having an aperture in the body thereof whereby to permit projection of a finger therethrough for engagement with the placard for removal thereof. 95

3. In combination, a holder, a placard adapted to be removably positioned therein, and a bracket secured thereto, said holder comprising a base plate having the marginal edge portions thereof inturned whereby to provide pairs of inwardly extending flanges, each flange of each pair being arranged in parallel relation to the other flange of the same pair, one of said flanges having the opposite end portions thereof spaced from the opposite end portions of the flanges of the other pair, the flange opposing said one flange being relatively wider than said one flange, said one flange having one end thereof spaced a greater distance from the adjoining flange than the opposite end whereby to provide a drain opening. 105 110 115

In testimony whereof I hereunto affix my signature.

CLARENCE H. HAGAN.
